C. A. FETTERS

WASHBOARD

Filed June 15, 1921

UNITED STATES PATENT OFFICE.

CHARLES A. FETTERS, OF WASHINGTON, DISTRICT OF COLUMBIA.

WASHBOARD.

Application filed June 15, 1921. Serial No. 477,704.

To all whom it may concern:

Be it known that CHARLES A. FETTERS, a citizen of the United States, residing at Washington, in the District of Columbia, 5 has invented certain new and useful Improvements in Washboards, of which the following is a specification, reference being had therein to the accompanying drawing.

The invention relates to wash boards of 10 the type used by travelers for washing small articles of apparel in hotels and the like, and has for its object to provide a device of this character formed from rubber so that the same can be rolled into a compact package 15 for storage in a traveling bag or suit case. Also to provide vacuum cups on the back of the wash board, thereby providing means whereby the board may be attached to a wash tub, or to a wash basin.

20 A further object is to locate the vacuum cups on the back of the board in registration with the bottoms of the convolutions of the rubbing surface of the wash board, so that as an article is rubbed upwardly or 25 downwardly on the rubbing surface, there will be an outward pull on the vacuum cups instead of a sliding movement.

With the above and other objects in view the invention resides in the combination and arrangements of parts as hereinafter set 30 forth, shown in the drawings, described and claimed, it being understood that changes in the precise embodiment of the invention may be made within the scope of what is claimed without departing from the spirit 35 of the invention.

In the drawings:—

Figure 1 is a perspective view of the wash board, showing the same attached to the side of a wash tub.

40 Figure 2 is a vertical sectional view taken on line 2—2 of Figure 1.

Figure 3 is a horizontal sectional view taken on line 3—3 of Figure 1.

45 Figure 4 is an end view showing the wash board rolled and ready for storage.

Referring to the drawings, the numeral 1 designates the wash board, which is formed from rubber and 2 the rubbing surface thereof, the rubbing surface comprising 50 spaced transversely disposed ribs 3, over

which ribs articles are rubbed in the usual manner during a rubbing operation. Disposed on the back 4 of the wash board 1 are a series of horizontally disposed rows of 55 vacuum cups 5. Each row of vacuum cups is disposed in registration with the transverse channels 6 of the rubbing surface so that during an upward and downward rubbing operation, the transversely disposed 60 ribs 3 will cause an outward pull upon the material adjacent the vacuum cups which are disposed in registration with the channels 6. The wash board when it is desired to attach the same to a tub 7 is preferably 65 damped, then forced or pressed into engagement with the surface of the tub or wash basin to which it is to be attached. This will cause the vacuum cups 5 to bind 70 and hold the board in place. The board being in place, small articles can be easily 75 and quickly rubbed thereon.

When it is desired to roll the washboard into a compact package as shown in Figure 4, said board is rolled from the bottom 75 upwardly and in the direction of the rubbing surface 2, after which the snap fastener 7 is forced into the female portion 8 of the fastener, thereby holding the board 80 in rolled position.

From the above it will be seen that a board is provided which is compact and one which may be easily transported from place to place. At the present times small boards of this character are either constructed in accordance with the structure of 85 a conventional form of wash board and are a combination of metal and wood, or are stamped entirely out of metal. In either case they take up considerable room or 90 tear articles of apparel in hand bags or suit cases. By forming the washboard from rubber the washboard not only can be formed into an extremely compact package, but at the same time the nature of the material 95 from which the same is formed precludes the possibility of the same tearing articles of apparel.

The invention having been set forth what is claimed as new and useful is:—

100 1. A wash board formed from a single piece of pliable rubber, vacuum cup means

carried by the rear side thereof whereby said wash board may be attached and held on a smooth surface.

2. A wash board formed from a single piece of pliable rubber, one side of said rubber being provided with a rubbing surface comprising horizontally disposed ribs and grooves, and vacuum cups disposed on

the back of the washboard and in registration with the grooves and forming means 10 whereby the washboard may be attached to a surface.

In testimony whereof I hereunto affix my signature.

CHARLES A. FETTERS.
